US0D1040348S

(12) **United States Design Patent** (10) **Patent No.:** **US D1,040,348 S**
(45) **Date of Patent:** **** Aug. 27, 2024**

(54) **LIP IMPLANT**

(71) Applicant: **SurgiSil, L.L.P.**, Plano, TX (US)

(72) Inventors: **Peter Raphael**, Plano, TX (US); **Scott Harris**, Dallas, TX (US)

(73) Assignee: **SURGISIL, L.L.P.**, Plano, TX (US)

(**) Term: **15 Years**

(21) Appl. No.: **29/911,399**

(22) Filed: **Sep. 1, 2023**

Related U.S. Application Data

(63) Continuation of application No. 29/738,540, filed on Jun. 18, 2020, which is a continuation of application No. 29/491,550, filed on May 22, 2014, now Pat. No. Des. 979,060, which is a continuation of application No. 13/174,914, filed on Jul. 1, 2011, now abandoned, which is a continuation of application No. 11/929,267, filed on Oct. 30, 2007, now Pat. No. 7,993,409, which is a continuation of application No. 10/792,984, filed on Mar. 4, 2004, now Pat. No. 7,344,566, which is a continuation-in-part of application No. 10/384,229, filed on Mar. 7, 2003, now Pat. No. 7,008,455.

CLAIM

The ornamental design for a lip implant, as shown and described.

DESCRIPTION

FIG. 1 is a perspective view of a lip implant showing our new design, according to a first embodiment;

FIG. 2 is a perspective view of the lip implant showing our new design, according to a second embodiment; and,

FIG. 3 is a perspective view of the lip implant showing our new design, according to a third embodiment.

The broken lines in each of FIGS. 1-3 show portions of the lip implant that form no part of the claimed design.

FIG. 1

FIG. 2

FIG. 3
